COMBINED HAIR PIN AND FRAME FOR SETTING PIN CURLS

Wayne K. Fairchild, Montebello, Calif.

Application June 15, 1948, Serial No. 146,980

Term of patent 3½ years

(Cl. D86—10)

To all whom it may concern:

Be it known that I, Wayne K. Fairchild, a citizen of the United States, and a resident of Montebello, in the county of Los Angeles and State of California, have invented a new, original, and ornamental Design for a Combined Hair Pin and Frame for Setting Pin Curls, of which the following is a specification, reference being had to the accompanying drawing, forming a part thereof.

In the drawing:

Fig. 1 is a perspective view showing my new design of a combined hair pin and frame, for setting pin curls; and

Figs. 2 and 3 are, respectively, a rear elevational view and a front elevational view thereof.

What I claim is:

The ornamental design for a combined hair pin and frame for setting pin curls, as shown.

WAYNE K. FAIRCHILD.
